SPUDDING ASSEMBLY

Norman C. Ayers, Newark, Ohio

Application November 2, 1934, Serial No. 751,248

3 Claims. (Cl. 255—7)

This invention relates to certain new and useful improvements in spudding assemblies, and an object of the invention is to provide in an assembly of this kind an improved shoe which will pull with the cable instead of against the cable as is now the difficulty with the shoes generally employed, the shoe of the invention thereby insuring an even distribution of the pull by the jerk line along the line of the cable where it contacts with the shoe thus reducing to a minimum wear on both the cable and the shoe.

Further, in accordance with the present invention, a shoe is provided which may be attached to the cable in a more efficient way and with greater facility than now possible.

Further in accordance with the present invention, a spring assembly for the spudding organization is provided which will efficiently absorb any shock or jar imparted to the jerk line and will so take up the sudden force to which the line is subjected during the spudding operation as to reduce breakage and damage to the line at the same time insuring higher efficiency and lower maintenance costs.

The invention, together with its objects and advantages, will be best understood from a study of the following description, taken in connection with the accompanying drawings wherein:

Figure 1 is a side elevational view of the improved spudding assembly.

Figure 2 is a side elevational view of a spudding shoe and link assembly associated therewith.

Figure 3 is a side elevational view of the spring assembly.

Figure 4 is an elevational view of the shoe per se with certain parts removed.

Figure 5 is a detail sectional view taken substantially on the line 5—5 of Figure 4.

Referring to the drawings by reference numerals it will be seen that the spudding shoe indicated generally by the reference numeral 10 is of a shape corresponding substantially to the shape of the spudding shoe now generally used.

At the largest end thereof the shoe 10 is provided with the slot or groove 11 to accommodate the drill cable 12, and at one side thereof the shoe 10 is provided with a suitable recess 13 in which is pivoted a dog 14 that has one end extending into the slot 11 to engage the cable 12 in a manner to normally and yieldably retain the shoe engaged with the cable against slipping. The beveled free end of the dog 14 is normally urged into engagement with the cable 12 through the medium of a flat leaf spring 15 that at one end

is suitably embedded in the material of the shoe 10 and has a free end bearing against the dog 14 in the manner clearly shown in Figure 4. Protecting the dog 14 and substantially closing the recess 13 is a suitable plate 16 that is secured in place through the medium of screws or other suitable fastening means 17. For limiting rotative movement of the dog 14 in either of two directions, the same is provided with a lateral pin 18 that operates in a suitable slot 19 provided therefor in the plate 16. The pin 18 also serves as a handle for manually swinging the dog 14 against the action of spring 15.

By providing the slot 11 in one side of the shoe 10 it will be apparent that the shoe may be attached to the cable with ease. All that is necessary to attach the shoe to the cable is to slip the cable parallel with the slot on the shoe, fit the spring catch 15 open, and let the cable slide into the groove of the shoe. This procedure may all be accomplished by a single motion of the foot and be completed within a few minutes.

As is well known, when the jerk line is in a pulling position, the present shoes, being in one piece, will not give, and consequently will slide up and down the drilling cable within a certain confined area. This area is limited by what is known as a "bridle", the same being in the nature of a cable 20 that at one end is anchored to the floor 21 of the rig and at an opposite end is secured directly to the shoe in accordance with present practice. This continual sliding of the shoe on the cable tends to wear the cable as well as the shoe. To overcome this, instead of attaching the bridle 20 directly to the shoe, I provide a pair of pivoted links 22 and 23, the link 23 being pivoted to the shoe 10 while the link 22 is provided with a projection 22a to which is pivoted the bridle or cable 20 as shown in Figure 1. The links 22 and 23 forming an articulated connection between the bridle or cable 20 and the shoe 10 permits the jerk line to change its position as the crank rotates without the shoe sliding on the cable.

As is well known, all spudding or jerk lines to day are connected directly to the crank 24 of the band wheel 25. These lines have brought to light two big objections which have not as yet been eliminated. Manila lines were used due to the "give" of the rope, which absorbs part of the shock imparted on the line when the tools were suddenly lifted and dropped in the holes. The flexibility of the rope was quite sufficient to meet the needs of oil men, but the continual giving of the rope weakened the line and breaks were com-

monplace. For many years, oil men have endeavored to use a wire line. This practice has also proven unsatisfactory because, while the wire line would not break, yet it would not take up the shock which was imparted directly to the entire rig. To overcome these difficulties, I have provided an improved spring assembly 26 for operatively connecting the jerk line 27 at one end to the crank 24 of the band wheel 25.

10 The aforementioned spring assembly 26 comprises, as best shown in Figure 3, a wrist pin collar 28 that is secured through the medium of the wrist pin 29 engaged with a selected one of the openings in the crank 24, to the crank 24; a connection head 30 that at one end is equipped with a roller 30' about which is trained the jerk line 27 and which at its other end is bifurcated to receive the closed end of a U-bolt 31, a pin 31' serving to connect the U-bolt and connection head 30 in a manner clearly shown in Figure 3. Also, a second U-bolt 32 is provided and the same at the closed end thereof is received in the furcations of the bifurcated part of the wrist pin collar 28 and is engaged with said collar through the medium of a pin 33. Suitably arranged on and engaged with the U-bolts 31 and 32 are end caps 34 between which is interposed a coil spring 35 disposed about the U-bolts 31 and 32. The U-bolts 31 and 32, at the ends thereof, 30 are provided with suitable nuts 36 that act as stops for the collars 34. In this connection it will be apparent that the U-bolts 31 and 32 are mutually disengaged and are free to move longitudinally relative to one another and in reverse directions. Also, the spring 35 will be of just sufficient tension to permit the shock being absorbed and still permit the full pull made on the cable raising and lowering the tools in the drill hole. The size of the spring and the associated parts will of course vary as the situation demands. Too, the connection head 30 will be of such a shape and construction as to insure of maximum strength with minimum weight.

Completing the assembly is the roller 37 journaled in the bifurcated end of the aforementioned link 22 and about which is trained the jerk line 27 serving to connect the spring assembly 26 and the link assembly associated with the shoe 10.

What is claimed is:

1. In a spudding assembly including a shoe, an anchoring bridle for the shoe, a band wheel crank, and a jerk line, means on the shoe for releasably engaging the shoe with the well drilling cable, link means operatively connecting the shoe with the anchoring bridle and jerk line respectively, and a spring device for connecting the jerk line with the eccentric pin of the band wheel crank, said shoe being provided with a slot in one face thereof for receiving the drilling cable, and a spring dog pivoted to the shoe and extending into the slot for confining the cable within the slot, and said spring device including a collar member adapted to be engaged with the eccentric pin of the band wheel crank, a connection head having roller means for engagement with the jerk line, a longitudinally extensible connection between said collar and connection head, and including a spring member normally urging said collar and head away from one another. 10

2. In a spudding assembly, a shoe having a lateral cable receiving slot and a lateral recess opening at one end into the slot, a dog pivoted within the recess and having an end extending into the slot to engage the cable, a spring anchored within the recess and bearing against the dog to urge the same in one direction, a plate secured to one face of the shoe and disposed over said recess, said plate being provided with a slot, and a lateral pin on the dog operating in said slot. 25

3. In a spudding assembly, a spring device for connecting the jerk line with the eccentric pin of the band wheel crank of a spudding assembly, said spring device including a collar member adapted to be engaged with the eccentric pin of the band wheel crank, a connection head having roller means for engagement with the jerk line, and a longitudinally extensible connection between said collar and connecting head including a pair of mutually disengaged U-shaped members free to move longitudinally relative to one another and in reverse directions, end caps associated with said U-shaped members, and a coil spring disposed about said U-shaped members and interposed between said caps. 35
